Primary Examiner — Sandra Snapp*Assistant Examiner* — Jasmine L. Comedy(74) *Attorney, Agent, or Firm* — Price Heneveld LLP(57) **CLAIM**

The ornamental design for a canopy extension for office pod, as shown and described.

DESCRIPTION

FIG. 1 is a perspective view of a canopy extension for office pod according to the design;

FIG. 2 is a front elevation view thereof;

FIG. 3 is a back elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The broken lines represent environmental subject matter and form no part of the claimed design.

1 Claim, 7 Drawing Sheets(56)
